ELECTRIC SWITCH

James M. Anderson, Broomall, Pa., assignor to
 General Electric Company, a corporation of New
 York

Application December 12, 1942, Serial No. 468,782

6 Claims. (Cl. 200—89)

1

My improvement relates to improvements in electric switches and more particularly high speed circuit breakers and especially high speed automatic trip-free circuit breakers having a plurality of poles, which are independent of each other with respect to their circuit opening operation, and have a single operating mechanism for simultaneously actuating to the closed circuit position all poles fully open at any time.

Probably the greatest trouble experienced in the operation of mercury arc rectifiers arises from abnormal operating conditions such as an arc-back occasioned by reverse current flow from cathode to anode or by the striking of an arc discharge between anodes. The reversal of current flow establishes a short circuit which is fed not only by the other rectifying paths of the particular rectifier, but also by all the rectifiers operating in parallel with this rectifier. The rate of increase of current in this short circuit path is so high, particularly in large installations, that currents dangerous to equipment and personnel and destructive of service continuity are quickly reached. There have been observed rates of increase of current of over six million amperes a second for a single rectifier and over eleven million amperes a second where several are operated in parallel. It is, therefore, imperative to interrupt this short circuit current very quickly if the current at interruption is not to exceed a safe value and interruption of service is to be prevented. In short, the problem is to interrupt the circuit of the faulty anode so quickly as to limit the resulting current to a safe value. But parts such as the movable contact of the circuit breaker and associated members mechanically actuated fast enough to accomplish such quick circuit interruption must also be stopped quickly.

Also, the movement of such parts may be highly accelerated by magnetic forces due to the short circuit current being opened. The natural result is for these parts to rebound to the extent even that they may reclose the circuit and thereby reestablish the fault arc. This would be dangerous to both personnel and equipment. Buffers with a slowing or snubbing action sufficient to prevent serious rebound introduce space and time features which render them more or less impractical from the standpoint of space, performance, and cost considerations. Moreover, where a relatively small quick opening movement is important, the use of buffers to prevent rebound is not satisfactory since they would require a slowing down of the moving parts before the contact

2

gap was sufficient to insure the interruption of the fault arc.

An object of my invention is to provide, for circuit breakers and particularly high speed circuit breakers, an improved arrangement for preventing, at the time of the circuit opening operation, any substantial rebound of the movable contact and the parts associated therewith. Another object of my invention is to provide an improved anti-rebound arrangement which is applicable to either single pole or multipole circuit breakers and particularly multipole circuit breakers whose poles are independent of each other with respect to their circuit opening operation 10 but which have a single closing mechanism for simultaneously closing all poles that are open at any time. A further object of my invention is to provide an improved positive anti-rebound arrangement whose holding action is automatically 15 released during the resetting operation of the circuit breaker mechanism. A still further object of my invention is to provide an improved anti-rebound arrangement which is relatively simple and inexpensive. These and other objects of my 20 invention will hereinafter appear in more detail.

In accordance with my invention, I provide, for circuit breakers, an improved anti-rebound arrangement comprising two cooperating elements which are operative to engage each other 25 near the end of the circuit opening movement of the movable contact and by such engagement to hold the contact against appreciable movement toward the circuit closing position. Also in accordance with my invention, I so arrange these 30 cooperating elements that one has a stationary mounting and the other is mounted for movement with the movable contact of the circuit breaker. Further in accordance with my invention, I provide means for automatically releasing 35 the anti-rebound or holding action of these cooperating elements during the resetting operation 40 of the circuit breaker mechanism.

My invention will be better understood from the following description when considered in connection with the accompanying two sheets of drawings, and its scope will be pointed out in the appended claims.

In the accompanying drawings, Fig. 1 is a side elevation, partly broken away and partly in section, of a high speed automatic trip-free circuit breaker, shown in the closed position and embodying my invention; Fig. 2 is a view similar to Fig. 1 showing the position of the parts near the end of the circuit opening movement with the 55 anti-rebound effect in action; Fig. 3 is a view

similar to Fig. 2 showing the circuit breaker parts in the full open position with the resetting action completed preparatory to closing the circuit breaker and with the anti-rebound mechanism also reset; Fig. 4 is a front elevation, to an enlarged scale, partly in section of a portion of the circuit breaker mechanism illustrating my anti-rebound arrangement in more detail; and Fig. 5 is a front elevation in outline of a multipole circuit breaker having a plurality of pole elements like that shown in Figs. 1, 2 and 3, each provided with anti-rebound means embodying my invention.

In the single pole circuit breaker 6 shown in Figs. 1, 2 and 3 for the purpose of illustrating my invention, a base or panel 10 of suitable insulating material has suitably secured thereto spaced lower and upper contact studs 11 and 12, respectively, which are provided with terminals 13 and 14, respectively. The stud 11 comprises a stationary contact block 15 having a curved contacting surface 16, which, as shown, is cylindrical. The stud 12 comprises a contact block 17 in which is supported a plurality of relatively stationary contacts 18, only one of which appears in the drawing. Each of such contacts 18 is arranged for high pressure line contact with the stud block 17. For this purpose, each contact 18 is mounted with its upper end fitting somewhat loosely in a cylindrical recess 19 in the stud block 17. As shown more clearly in Fig. 1, the mounting for each contact 18 includes a headed screw 20 and a backing spring 21. The screw is supported in an opening in the stud 12 and screwed into the block 17. In order to maintain a sharp current loop at the contact recess 19, the head of the screw 20 is centered in the opening of the stud 12 by an insulating bushing, not shown. This prevents the passage of current from the block 17 through the screw 20 and the spring 21 to the stud 12. The spring 21 between the head of the screw 20 and the contact 18 provides a bias to hold the upper end 22 of the contact 18 forward against the face of the recess 19 in line-to-line contact. For better contact action, the upper end of the contact 18 and the surface of the recess 19 against which it bears is silver faced. Likewise, the lower end of the contact 18 is provided with a silver contact piece 23.

For completing a circuit through the circuit breaker, there is provided a contact 24, the plane surface 25 of which is fulcrumed on the cylindrical contacting surface 16 of the stationary contact 15 for movement into engagement with the relatively stationary contact 18 by a mechanism so constructed as to insure high speed circuit opening action. In the arrangement illustrated, the lower end of the contact 24 is provided with a plane contact surface 25 which bears on the cylindrical contact surface 16 of the contact block 15. Both of the contact surfaces 16 and 25 are silver faced for better contact action. At an intermediate point in its length, the movable contact 24 is provided with a silver contact portion 26, which is arranged to engage the silver portion 23 on each of the contacts 18. The contacts 18 are spaced slightly by separators 27 in order that each may be free to move independently of the others under the magnetic attracting forces between them due to the currents flowing through them in the same direction and thus come to a better bearing in the contact recess 19 and against the contact face 26 of the movable contact 24. The separators are preferably not of magnetic material but suitable insulating material may be used. In ad-

dition to the primary stationary contacts 18 there is also provided a secondary or arcing stationary contact 28 whose upper end is mounted in a cylindrical recess 29 in an arcing contact block 30 separated from the contact block 17 by suitable insulation. Like the primary stationary contacts 18, the secondary stationary contact 28 is biased forward to engage the arcing contact block 30 in line-to-line contact. For this purpose, there is provided one or more backing springs 31, which are mounted in holes in the stud 12. The backing springs 31 do not engage the contact 28 directly but are spaced therefrom by insulating rods 32. The lower end of the secondary stationary contact 28 and the upper end of the movable contact 24 are provided with suitable contact portions 33.

For arc extinguishing purposes, the arcing contact block 30 is provided with an arcing horn extension 34 and is, also, connected to the stud 12 through a blowout coil 35. For carrying the end of the arc off from the contact portion 33 of the movable contact 24, there may be provided, as will be obvious to those skilled in the art, a blowout coil connected between an arcing horn, not shown, and the lower stud 11 of the circuit breaker. The arc extinguishing structure further includes two enclosing barriers 36, only one of which is partially shown in the drawings.

In order that the plane face 25 of the movable bridging contact 24 may pivot on the cylindrical face 16 of the contact block 15, the contact 24 is mounted on suitable supporting means, such as a cradle 37, pivoted to rotate about an axis which is substantially in line with the element of the cylindrical surface 16 about which the contact pivots as a line contact. In other words, the construction is such that the pivotal axes of the contact 24 and the cradle are as nearly coincident as possible in order to reduce the sliding between and consequent wear of the contact surfaces 16 and 25 to a minimum. As shown, this cradle comprises two spaced side members 37, only one of which appears in the drawings. Each of these is supported on a pivot 38 mounted in the side 39 of the circuit breaker frame adjacent the side member of the cradle. At the upper end, the side members 37 are joined by a pivot 40, which passes through the contact 24 and leaves this contact free to be biased against the contact surface and for high speed of opening operation. It will be noted that in the circuit closed position of the contact structure described, the magnetic loop expansion effect produced by any current through the circuit breaker increases the pressure between the contacts as long as the cradle 37 is maintained in the closed circuit position and, consequently, tends to accelerate contact separation when the cradle is free to rotate clockwise about its pivots 38.

In order to move the cradle 37 into and maintain it in the closed circuit position and yet have it quickly freed for high speed interruption, there is provided a movable abutment 41, releasable means comprising a latch 42 pivoted in the frame 39 at 43 for holding the abutment 41 in a predetermined position, and actuating means comprising a member 44 movable on the abutment 41 and between the abutment and a member 45 movable with the bridging contact 24, for example, pivoted on the cradle 37. In order to minimize friction and facilitate high speed operation, the members 44 and 45 are preferably rollers, as shown. The abutment 41 is mounted on a pivot 46 extending between the sides 39 of the circuit

breaker frame. In order to obtain the counter-clockwise movement of the cradle 37 necessary to bring the contact 24 into the normal current-conducting position, the abutment 41 is provided with a suitably shaped cam face 47, which is traversed by the roller 44.

For actuating the roller 44, there is provided an operating member 48 which, as shown, is mounted on the pivot 46 and is connected to the roller 44 through one or more operating links 49. 10 These links are pivoted to the operating member 48 at 50 and to the roller 44 at 51. The operating member comprises two side pieces 48 and a cross-connection 52, which in the closed position of the circuit breaker abuts the frame 39 at 53, as shown in Fig. 1. In order to maintain the circuit breaker in this closed position as long as the abutment 41 is maintained in the latched position, the parts are so proportioned and arranged that in the closed position of the circuit breaker 20 the direction of pressure on the roller 44 tends to force this roller to the right on the cam surface 47 so as to provide the necessary holding bias.

For releasing the latch 42 so as to effect the opening of the circuit breaker, there is provided electromagnetic means responsive to a predetermined abnormal condition of the circuit controlled by the circuit breaker. The particular means illustrated is responsive to a predetermined direction of flow of direct current. As shown, this means comprises two U-shaped cores 54 and 55 of suitable magnetic material. The core 54 has leg portions 540 and 541 which are interconnected by a cross portion 542. Only one of the leg portions 550 of the core 55 appears in the drawings. These leg portions are interconnected by a cross portion 552 which appears in Fig. 1. The cores 54 and 55 are arranged substantially perpendicularly to each other and have two common polar extensions 56, only one of which appears in the drawings, with an air gap arranged to be bridged by an armature 57. The core 54 is secured to the frame 39 so as to embrace the stud 11 and is accordingly energized responsive to the magnitude and direction of the current flowing through the circuit breaker. The core 55 is energized by polarizing windings 58 only one of which appears in the drawings. These windings are arranged one on each leg of the magnet and energized preferably from a source of direct potential although rectified alternating current may be used. The flux of these polarizing windings alone is sufficient to maintain the armature 57 in the attracted position against the bias of a latch actuating spring 59, which pushes against the tail of the latch 42 through a collared rod 60 passing through the armature 57. A turned down portion of the rod 60 passes through the armature 57, the shoulder on the rod where the diameter is reduced being employed to move the armature 57 away from the magnet pole faces because of the bias of the spring 59 on the occasions of predetermined current conditions in the breaker. The magnetic structure and arrangement is such that when current flows through the circuit breaker in a predetermined direction the flux due to the current is additive in its effect to the armature holding effect of the flux due to the windings 58. However, when current flows through the circuit breaker in a direction opposite to said predetermined direction, the two fluxes not only are subtractive in their resultant holding effect, but also are so shifted that the armature 57 is quickly released to trip the latch 42 under the action of

the spring 59. The bias of the spring may be controlled by a nut 61 threaded on a spring support 62, which may also serve to secure the removable bottom of the U-shaped magnetic structure to the stud 11, as shown. The weight of the armature 57 and the movable parts directly associated therewith is reduced to a minimum in order to expedite the circuit opening action of the circuit breaker.

For resetting or returning the armature 57 to the attracted position during the opening of the circuit breaker, I provide means responsive to the movement of the abutment 41. As shown, this means comprises a link 63 pivoted at 64 to the abutment 41 and to the latch 42 at 65 through a slotted opening 66, the purpose of which is to allow a desired counterclockwise movement of the abutment before resetting the armature. As shown in Fig. 4, this link 63 actually comprises two parallel spaced members. In order to prevent undue shock to the armature 57 during the resetting movement, there is provided a shock absorbing spring 67 around the stem of the rod 60 on the side of the armature away from the polar extensions 56. The plug 68, screwed into the frame, provides a shoulder stop for the armature 57 so that the armature can not compress the spring 67 to its solid height as the armature moves and thereby strip the collar 69 secured to the rod 60 therefrom. For resetting the abutment 41 and the latch 42 to the sustaining position, I provide abutment return springs 70 and a latch return spring 71. The former is secured to the abutment pivot 64 and to the frame 39 and tends to turn the abutment clockwise about its pivot 46. The latch return spring 71 is connected between the latch 42 and the frame 39 and tends to turn the latch clockwise about its pivot 43.

For effecting a quick movement of the contact 24 to the open circuit position, exerting pressure between the contact surfaces 16 and 25 at all times, and also recompressing the tripping spring 59, there is provided suitable energy storing means, such as biasing springs 72, only one of which appears in the drawing. These springs are positioned outside of the cradle 37. In order to have them suitably stressed during the closing movement of the breaker, they are connected between a stud 73 supported in the sides of the frame 39 and a rod 74 fixed in the movable contact 24 but extending through slotted openings, not shown, in the cradle sides 37 so as to permit a predetermined movement of the contact 24 relatively to the cradle 37. For exerting pressure between the contact surfaces 16 and 25 at all times and also returning the operating member 48 and the parts connected thereto to the position shown in Fig. 3, there is provided suitable energy storing means, such as a biasing spring 75. In order to have this spring suitably stressed during the closing movement of the circuit breaker, it is connected between the pivot 59 and a rod 76 fixed in the contact 24 which is provided with a hollow portion for receiving the end of the spring.

Since mercury arc rectifiers usually have six anode circuits and sometimes more, the illustrated circuit arrangement is such that a plurality of single-pole circuit breakers in the open circuit position can be closed simultaneously, and also any one or more poles can open and can be closed without interfering with the poles that are closed whereby to avoid unnecessary interruptions in sound anode circuits. For this purpose, each pole is provided with an actuating lever 77 pivoted

at 48 and these levers are interconnected by a common actuating means comprising a crossbar 78. As shown, the actuating lever 77 is U-shaped with a cross piece 79 having a projection 80 arranged to abut the cross piece 52 of the operating crank 48. In order to insure that each pole will be positively closed, the projection 80 is adjustably positioned so as to take care of manufacturing tolerances and variations in lost motion whereby to insure the desired closing action of any one or more poles even though the others are closed. The projection 80 is so adjusted that a predetermined clockwise movement of the actuating lever 77 will impart sufficient clockwise movement to the operating crank 48 to effect the holding bias of the rollers. This, in general, will cause the operating crank 48 to settle with its cross piece 52 abutting the frame 39 at 53 with some clearance between the projection 80 and the cross piece 52. However, it is possible that the final holding biased position of the crank 48 may be reached at the end of the clockwise movement of the actuating lever 77. In this case, the projection 80 may continue to abut the operating crank cross piece 52.

For actuating the crossbar 78 to effect the resetting of the releasable means comprising the abutment 41 and the latch 42 and reclosing all poles open at any time, the crossbar 78 is actuated first counterclockwise and then clockwise about its pivot 46. As will be apparent to those skilled in the art, this actuation may be performed either by manually operated mechanism or by motive power mechanism or both suitably connected to an operating rod 81 which, as shown, is pivotally connected to a crank 82 secured to the crossbar 78.

Because of the relatively small mass of the moving parts, the fast operation of the tripping mechanism and the strong opening bias on the movable contact 24, it will be apparent that this contact moves to the circuit opening position very fast. In order to prevent any tendency for this contact to rebound in the closing direction enough to reestablish an arc, I provide, in accordance with my invention, two cooperating elements 83, 84 which are operative to engage each other near the end of the circuit opening operation and thereby to hold the contact 24 against any substantial movement in the circuit closing direction. As shown, these elements are cooperating latching devices and, in accordance with my invention, one of the elements is in the form of a latch 83 which is mounted to partake of the movement of the contact 24. For this purpose, the latch 83 may be pivotally supported on a reduced diameter of the hub of the roller 45, as more clearly shown in Fig. 4. The other element is in the form of a projection or catch 84 which, in accordance with my invention, has a stationary mounting. For this purpose, it may be mounted, as shown more clearly in Fig. 4, on the side of the circuit breaker frame 39 or as a part of a support 85 which is rigidly secured to this frame by suitable means, comprising, as shown, cap screws 86 and 86' and lock washers 87. The latch 83 is provided with a hook portion 88 which is arranged to engage the catch 84 as the movable contact 24 moves to the circuit open position. For this purpose, the latch 83 is biased for counterclockwise rotation by suitable means such as a spring 89 which extends between the latch and an arm 90 on the actuating lever 77. This spring 89 maintains the tail 91 of the latch 83 in abutting engagement against the stationary projec-

tion 84 while the circuit breaker is closed and biases the hook portion 88 into interlocking engagement with this projection near the end of the circuit opening movement of the contact 24 so as to prevent any material rebound thereof. In order better to guide the latch 83 in its plane of rotation, the projection 84 may be provided with shoulder portions 92 as shown in Fig. 4.

Since the latch or hook element 83 positively holds the movable contact 24 in the open circuit position in consequence of its engagement with the catch 84, it is necessary to disengage these latching elements before the circuit closing operation can be effected. In order to effect this disengagement, I provide, in accordance with my invention, means for releasing the latch 83 from the catch 84 during the resetting operation of the circuit breaker tripping and holding mechanism. As shown, this means comprises a projection or pin 93 which is mounted on the latch resetting links 63 in the path of movement of the tail 91 of the latch 83 when it is in the holding position. Consequently, during the resetting operation when the links 63 move from right to left under the bias to which they are subjected, the latch 83 is turned clockwise out of engagement with the catch 84 and positively held out of such engagement during the closing operation of the circuit breaker. When the circuit breaker is closed, then the tail 91 of the latch 83 abuts the catch 84.

Assuming the circuit breaker closed with the parts positioned as shown in Fig. 1 and current flowing through the circuit breaker in the direction which causes the flux of the electromagnet 55 to assist the flux of the polarizing electromagnet 56 to hold the armature 57 in the attracted position against the bias of the tripping spring 59, then, if the direction of the current flowing through the circuit breaker is reversed as in the case of an arc-back in the anode circuit of a mercury arc rectifier, the armature is quickly released because of flux opposition and shift in the common magnetic path including the air gap bridged by the armature. The effect of the strong tripping spring 59 is to move the latch 42 forcibly counterclockwise about its pivot 43 thus releasing the abutment 41. Since there is no longer any support for the left-hand or free end of the abutment 41, the tension of the opening springs 72 and to a certain extent, the springs 75 and the contact springs 21 and 31 together with the weight of the parts bearing on the abutment 41 forces this member to turn in a counterclockwise direction about its pivot 46 whereby quickly to effect the opening of the circuit breaker with the parts positioned as shown in Fig. 2.

During this opening movement, the latch 83 moves downwardly in consequence of the clockwise rotation of its pivotal support about the pivot 38. Accordingly, the tail 91 of the latch is below the catch 84 and therefore, under the bias of the spring 89, the latch 83 is turned counterclockwise with its hook 88 under the catch 84. The movable support 37 of the contact 24 is consequently positively held in the open circuit position so that no rebound of this contact, except the very slight amount resulting from the necessity for mechanical clearances, can occur. In the holding position, the tail 91 of the latch 83 is positioned in the path of movement of the projection 84 on the resetting links 63.

In the position shown in Fig. 2, the bias on the roller 44, which was away from the panel 10, that is, in a direction to hold the circuit breaker

closed, is now directed toward the panel. If, after the opening of the circuit breaker, the crank 82 is rotated counterclockwise about its pivot, as by an upward movement of the operating rod 81, then the crossbar 78 is raised to the position shown in Fig. 3 with the actuating lever 77 turning counterclockwise about its pivot 46. While this motion is going on, the remaining tension on the spring 75 turns the operating crank 48 counterclockwise about its pivot 46 so that the roller 44 under its bias toward the panel moves to its lowest position on the cam surface 47 of the abutment 41. During this movement, the abutment 41 and its sustaining latch 42 are returned to the latching position under the biasing actions of their respective springs 70 and 71. As the links 63 move from right to left under the bias of the springs 70, the projection 93 on one of the links engages the tail 91 of the latch 83 and turns this element clockwise sufficiently to have its hook 88 clear the projection 84 and maintains this clearance until the circuit breaker is closed. In other words, the circuit breaker mechanism is reset as shown in Fig. 3 and ready for the actual closing movement to the position shown in Fig. 1. This is accomplished by a downward pull on the rod 81 either manually or otherwise as desired. This downward movement of the operating rod 81 turns the actuating crank 77 clockwise about its pivot 46. With this movement of the actuating crank, the projection 80 engages the transverse portion 52 of the operating crank 48 to rotate this member clockwise about its pivot 46. As this motion takes place, the roller 44 travels along the cam surface 47 in contact with the roller 45 to force the cradle 37 to turn counterclockwise about its pivot 38 and thereby to effect the engagement of the contact 24 with the contacts 18 and 28. During this movement, the springs 72 and 75 are stressed in preparation for the next opening action and also to maintain the desired contact pressure between the contact surfaces 16 and 25. The parts are then again in the circuit closing position shown in Fig. 1.

When a plurality of circuit breaker poles 6 are under the control of the crossbar 78, as shown in Fig. 5, each pole that may open automatically during movement of the crossbar will be closed by the downward movement thereof provided the self-resetting mechanism of the opened pole can move from the position shown in Fig. 2 to the reset position shown in Fig. 3 before the movement of the crossbar has proceeded so far as to prevent such resetting action.

Furthermore, assuming a plurality of poles, each provided with its own anti-rebound arrangement embodying my invention, it will be noted that the movable contact 24 of any pole, which opens during the downward or closing movement of the actuating rod 81 to close one or more other poles, will be held by its respective latching elements long enough to prevent rebound regardless of the position of the actuating lever 77.

It will be noted that the time during which the anti-rebound members 83 and 84 are in locking engagement depends on the position of the actuating lever 77 at the time a pole opens. The minimum time will, of course, occur when the actuating lever 77 is near the upper or resetting position shown in Fig. 3 during the reclosing action of some opened pole. If at this time another pole opens, the duration of the anti-rebound action in this last opened pole is the minimum and is determined by the time necessary for the operating

crank 48 and the parts attached thereto and movable therewith and, also, the abutment 41 and the resetting links 63 to move under the bias of springs 75 and 70, respectively, from the position shown in Fig. 2 to the reset position shown in Fig. 3. It will be apparent that, since the co-operating latching element 84 for each pole has a stationary mounting and is therefore unaffected by any movement of the parts of other poles or the operating mechanism itself, the anti-rebound or latching movement of the individual latch 83 of each pole is independent of the mechanism of the other poles.

While I have shown and described my invention in considerable detail, I do not desire to be limited to the exact arrangements shown, but seek to cover in the appended claims all those modifications that fall within the true spirit and scope of my invention.

20 What I claim as new and desire to secure by Letters Patent of the United States is:

1. A circuit breaker comprising a movable circuit controlling member biased to the open circuit position, means for holding said member in the closed circuit position, means for effecting the release of said holding means, and means for preventing rebound of said member from its open circuit position comprising two cooperating engaging elements, one being stationary and the other mounted to move simultaneously with said member and having a tail portion arranged to abut said one element when said member is in the closed circuit position and a catch portion arranged for interlocking engagement with said one element near the end of the circuit opening movement of the member, and resilient means biasing said other element into said abutting and interlocking engagements.

2. An electric switch comprising a movable circuit controlling member biased to the open circuit position, a self-resetting collapsible mechanism for maintaining said member in the closed circuit position comprising a movable abutment and a link pivotally supported thereon, means for effecting the collapse of said mechanism, and means for preventing rebound of said member from its open circuit position comprising a stationary element and a catch mounted to move simultaneously with said member, said catch having a tail portion arranged to abut said element when said member is in the closed circuit position and a hook portion adapted to interlock with said element near the end of the circuit opening movement of the member, resilient means biasing said catch into said abutting and interlocking engagements, and means on said link engageable with the tail portion of said catch at the beginning of the resetting movement of said collapsible mechanism to move the catch from interlocking engagement with said element to abutting engagement therewith.

3. An electric switch comprising two cooperating contacts, trip-free mechanism for effecting relative movement of said contacts comprising a pivoted support for one of the contacts, a first roller mounted on said support, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, means for effecting the release of said holding means whereby to cause the

11

circuit opening movement of said one contact, means for preventing rebound of said one contact from its open circuit position comprising a catch pivotally mounted on said pivoted support and a stationary element engageable by said catch near the end of the circuit opening movement of said one contact.

4. An electric switch comprising two cooperating contacts, trip-free mechanism for effecting relative movement of said contacts comprising a pivoted support for one of the contacts, a first roller mounted on said support, an abutment having a surface of a predetermined contour, releasable means for holding said abutment in a predetermined position, a second roller movable in one direction over the surface of said abutment between the abutment and said first roller to effect the circuit closing engagement of said contacts when the abutment is held in said predetermined position, means for effecting the release of said holding means whereby to cause the circuit opening movement of said one contact, means for preventing rebound of said one contact from its open circuit position comprising a catch pivotally mounted on said pivoted support and a stationary element engageable by said catch near the end of the circuit opening movement of said one contact, and means operable upon movement of said second roller over said surface in the reverse direction to move said catch out of engagement with said stationary element.

5. An electric switch comprising two cooperating contacts, trip-free mechanism for effecting relative movement of said contacts comprising a pivoted support for one of the contacts, a first roller mounted on said support, an abutment having a surface of a predetermined contour, releasable means for holding said abutment in a predetermined position, a second roller movable

12

in one direction over the surface of said abutment between the abutment and said first roller to effect the circuit closing engagement of said contacts when the abutment is held in said predetermined position, means for effecting the release of said holding means whereby to cause the circuit opening movement of said one contact, means for preventing rebound of said one contact from its open circuit position comprising a catch pivotally mounted on said pivoted support and a stationary element engageable by said catch near the end of the circuit opening movement of said one contact, and means operable upon movement of said second roller over said surface in the reverse direction to move said catch out of engagement with said stationary element and to reset said releasable means to the holding position.

6. A circuit breaker comprising a contact, a pivoted support on which said contact is pivotally mounted, means biasing said support for movement in a direction to effect the circuit opening movement of said contact, means for holding said support to maintain said contact in the closed circuit position, means for effecting the releasing of said holding means, and means for preventing rebound of said support and contact from the open circuit position comprising two cooperating elements, one being mounted stationary and the other mounted on said support to move simultaneously therewith and having a tail portion adapted to abut said one element when the contact is in the closed circuit position and a catch portion adapted to interlock with said one element near the end of the circuit opening movement of said member, and resilient means for biasing said other element into said abutting and interlocking engagements.
